UNITED STATES PATENT OFFICE.

JUSTUS C. GOOSMANN, OF CHICAGO, ILLINOIS.

SHELL-CONDENSER COUPLING.

Original application filed August 24, 1921, Serial No. 494,762. Divided and this application filed July 31, 1922. Serial No. 578,627.

To all whom it may concern:

Be it known that I, JUSTUS C. GOOSMANN, a citizen of the United States, residing at Chicago, in the county of Cook and State 5 of Illinois, have invented certain new and useful Improvements in Shell-Condenser Couplings, of which the following is a specification.

This invention relates generally to couplings or connections, and particularly to 10 a coupling for shell condensers, this application being a division of my co-pending application, Serial No. 494,762, filed August 24, 1921.

One of the purposes of this invention is 15 to provide for the connection to a heat exchange apparatus, such as a shell condenser adapted for use in refrigerating systems, of the pipes which communicate with 20 the condenser so that a strong and durable connection will be made which will not be liable to leak under pressure, and which can be readily assembled and readily disconnected and taken apart when occasion 25 requires.

Another object is to provide a coupling 30 which can be economically manufactured and which will effectively withstand the strains imposed thereon by expansion and 35 contraction of the parts which are caused by differences in temperatures of the contents of the condenser and pipes.

A preferred embodiment of the invention 40 is illustrated in the single figure of the drawings, which is a fragmentary sectional view of a condenser equipped with my invention.

Referring to the drawings, reference 45 character 3 indicates generally a cylindrical casing forming a shell, in which the cooling coils and other apparatus of the condenser, are disposed. The lower end of this casing is interiorly threaded to accommodate a plug 4 forming the bottom of the 50 chamber, and leakage around the plug is prevented by filling in the groove between the bottom of the casing and the plug with hard solder, as indicated at 5. The lower end of the shell is strengthened by a heavy 55 ring 6 which is shrunk onto the shell, and the whole structure is mounted in a standard or base 7, comprising an upwardly extending split flange 8 adapted to surround the casing, and in which the casing 60 is clamped by bolts 9.

The bottom plug 4 is provided with passages 11 and 12, forming the inlet and outlet to the chamber. When the apparatus is used as a condenser, the fluid (such as carbonic acid gas) which is delivered 60 under pressure from a compressor, a fragment of which is indicated by reference character 10, is conducted through a pipe 13 to the passage 11 from which it is delivered into the chamber near the top thereof by a vertically disposed pipe 14. The liquid accumulating in the bottom of the chamber enters the passage 12 through a radially perforated pipe 15 projecting a limited distance into the chamber and is 65 delivered to the expansion coils or other point of use through a delivery pipe 16.

The bottom plug 4 is also provided with a centrally disposed opening through which the pipe 17 projects. The upper end of 70 the pipe is connected with the coils as will be later explained, and the lower end has threaded thereon a nut or ring 18. Leakage around the pipe 17 is precluded by a packing ring 19 preferably made of type 80 metal. A hollow head 21 is adapted to surround the nut 18, and leakage between the head and the nut is guarded against by a packing ring 22 preferably of vulcanized fibre. A plurality of bolts 23 passed through the head and threaded into tapped 85 openings 24 in the bottom 4 are utilized to draw the head toward the bottom, thus compressing the packing rings 19 and 22, so as to insure leak proof joints at the 90 bottom of the apparatus.

The cooling liquid, such as water, for instance, in a refrigerating system is delivered 95 to the bottom of the apparatus from a supply pipe 25 which is connected through an elbow 26 with the head 21. The liquid is supplied to this pipe from any suitable source through a pipe 20 and has connected thereto a discharge pipe 27 equipped with a shut off valve 28 and in normal operating of 100 the apparatus the valve 29 in an extension of pipe 25 is opened and valve 28 is closed to insure flow of the cooling liquid upwardly into the apparatus.

The upper end of pipe 17 is connected with 105 a header 31 to which the internested coils 32, 33 and 34 are connected to convey the cooling medium upwardly through the condenser. The coils are connected at their upper ends with a discharge pipe, all as dis- 110

closed in my prior application previously mentioned, and this discharge pipe is connected with pipe 20 through a cross-connecting pipe 25 equipped with a valve 36 for the purpose explained in my prior application.

It will be apparent that in this construction any leakage around the pipe 17 is precluded by the gaskets 19 and 22 which may be compressed as tightly as desired by turning up the bolts 23. Furthermore, the joints will not be loosened by expansion or contraction of the pipe 17 since any movement of the pipe will be transmitted to the inner end thereof, while the outer end remains in fixed relation with respect to the plug 4.

The details of construction illustrated and described may be varied within considerable limits within the scope of the invention, and while the invention is shown applied to a 20 shell condenser, it is obviously capable of many other uses.

I claim:

1. In a device of the character described, the combination of a cylindrical casing, a bottom threaded into the lower end thereof, 25 means for clamping the lower end of the

casing, means for sealing the joint between said bottom and casing, a pipe extending through said bottom, a nut upon the projecting end of the pipe, a cap disposed over said nut, packing rings interposed between said nut and said bottom and said nut and said cap, respectively, and means for clamping said cap to said bottom to compress said packing rings.

2. In a device of the character described, the combination of a casing provided with an opening in one wall thereof, a pipe extending through said wall and movable relatively thereto, said wall being provided with a recess on its outer face surrounding said pipe, a nut threaded onto the outer end of the pipe, a cap disposed over said nut and provided with an opening aligned with said pipe and with a recess surrounding the inner end of said opening, a gasket disposed in each of said recesses at the ends of the nut, and means for drawing said cap toward said wall to simultaneously compress both of said packings against the nut.

JUSTUS C. GOOSMANN.
